UNITED STATES PATENT OFFICE.

WALLACE J. HOTCHKISS, OF ALPENA, SOUTH DAKOTA.

HANDLE.

1,379,020.

Specification of Letters Patent. Patented May 24, 1921.

Application filed February 21, 1921. Serial No. 446,678.

To all whom it may concern:

Be it known that I, WALLACE J. HOTCHKISS, a citizen of the United States, residing at Alpina, in the county of Jerauld and 5 State of South Dakota, have invented certain new and useful Improvements in Handles, of which the following is a specification, reference being had to the accompanying drawings.

10 This invention relates to handles and more particularly to handles for the doors of stoves, furnaces, etc.

An object of the invention is to provide a handle of this character which is connected 15 to the door and so arranged that it does not receive the heat generated within the stove or furnace, so that it may be readily grasped by the operator without danger of burning the hand of the operator.

20 Another object is to provide a handle of this character which is connected to the door of the stove and so disposed that the grip portion of the handle does not come in contact with the heated surface of the door or 25 wall of the stove.

A still further object of the invention is to provide a handle of this character which is connected to the door and held in spaced relation thereto so that the operator may 30 open and close the door without requiring the hand to be disposed adjacent the heated surface of the door.

A still further object of the invention is to provide a handle of this character which 35 permits the operator to open and close the door without stooping.

With these and other objects in view the invention consists in the improved construction and arrangement of parts to be herein- 40 after more particularly described, fully claimed and illustrated in the accompanying drawings, in which:

Figure 1 is a view in elevation of a handle constructed in accordance with an embodiment of the invention, and showing the handle applied to a stove door.

Fig. 2 is a side elevation of the handle applied,

Fig. 3 is a detail view of the supporting 50 band of the handle,

Fig. 4 is a vertical elevation of the hand grip, and

Fig. 5 is a section taken on the line 5—5 of Fig. 4.

55 Referring to the drawings, 5 designates a supporting plate which is secured to an oven

door A by fastening means 6 such as rivets or bolts. This plate may be secured at any convenient point from the free edge of the door to the longitudinal center, as shown in 60 Fig. 1. The plate 5 is provided with a lug 7 which extends at right angles to the plate, said lug having an opening 8 for the reception of one end of a chain 9. This chain may be of any type and length desired. 65

In order to permit the door A to be readily opened without requiring the hand of the operator to come in contact therewith, there is provided a novel hand grip 10 substantially rectangular in cross section, the said 70 hand grip being constructed preferably of wood and having its rear face provided with a pair of recesses 11 of a size to receive the fingers of the operator, so that the operator may grasp the handle firmly. The grip 75 10 is connected to the chain 9 by a connecting band 12, said band being substantially rectangular and having a lug 13 projecting from the upper face thereof, said lug having an opening 14 adapted to receive the end 80 link of the chain 9, the rear portion 15 of the band 12 being considerably thicker than the front portion of the band, so that said rear portion projects beyond the rear surface of the hand grip 10 to provide a spacer. 85

The hand grip 10 is disposed with its rear face parallel to the portion 15. The spacer 15 is adapted to engage the stove so as to hold the hand grip in spaced relation thereto, and prevent the hand grip from being 90 heated. In addition to this, the spacer cooperates with the hand grip to provide an opening between the stove and the rear face of the hand grip sufficient to admit the fingers of the hand of the user, and in this way 95 the fingers may be disposed within the recesses 11 without coming in contact with the stove so that the chain may be moved away from the stove and upwardly to open and close the door. When the hand grip 10 is 100 released, in view of the position of the lugs 7 and 12, the hand will be normally disposed in the positions shown in Figs. 1 and 2, thus preventing the hand grip 10 from coming in contact with the heated surface of the 105 stove. In addition to this, the grip is also positioned in spaced relation to the door A, so that the transmission of heat from any source to the hand grip is prevented, and as the hand grip is relatively large there is no 110 danger of the same slipping from the hand of the operator.

From the foregoing it will be readily seen that this invention provides a novel form of handle capable of being readily applied to the door of any stove, furnace or like device in which heat is confined, to permit the door to be readily opened and closed without requiring the use of a glove or cloth to prevent the hand from being injured. In addition to this, the hand grip is so positioned that it does not receive the heat from the stove.

What is claimed is:

A handle of the character described comprising a supporting plate, a lug projecting from one face of the supporting plate, a

chain having one end connected to the lug, a connecting member having a lug projecting from one face and adapted to be connected to the opposite end of the chain, a hand grip disposed in said connecting member, said hand grip extending beyond each end of the connecting member, one face of said connecting member extending beyond the adjacent face of the hand grip, to prevent contact of the hand grip with the support of the supporting plate.

In testimony whereof I hereunto affix my signature.

WALLACE J. HOTCHKISS.
